Term of patent 7 years

U.S. Cl. D55—1
Int. Cl. D15—01; D12—14

FIG. 1.

FIG. 2.

FIG. 3.

FIG. 4.

FIGURE 1 is a top plan view of the air cleaner cover; FIGURE 2 is a bottom view of the air cleaner cover; FIGURE 3 is a side elevational view of the air cleaner cover; and

The dominant features of my design reside in the portions shown in full lines, and the air cleaner element shown in FIG. 3 is included for illustrative purposes only.

I claim:

The ornamental design for an air cleaner cover, substantially as shown and described.
